Lacy Lacy, Attorney

UNITED STATES PATENT OFFICE.

FRED L. TICE AND CARL TICE, OF KINGFISHER, OKLAHOMA.

HAND OILER.

Application filed November 12, 1924. Serial No. 749,507.

To all whom it may concern:

Be it known that we, FRED L. TICE and CARL TICE, citizens of the United States, residing at Kingfisher, in the county of 5 Kingfisher and State of Oklahoma, have invented certain new and useful Improvements in Hand Oilers, of which the following is a specification.

This invention relates to an improved hand 10 oiler and seeks, among other objects, to provide a device wherein, upon the opening of the discharge valve of the oiler, oil will be forcibly delivered from the oiler can.

The invention seeks, as a further object, 15 to provide an oiler wherein the discharge tube of the device may be readily cleaned so that the device may easily be kept in good working condition.

And the invention seeks, as a still further 20 object, to provide a device wherein the pump employed will be mounted upon the filler tube of the can and wherein the pump may be readily removed to permit of the filling of the can.

25 Other and incidental objects will appear hereinafter.

In the accompanying drawings:

Figure 1 is a vertical sectional view 30 through our improved hand oiler.

Figure 2 is a vertical sectional view taken substantially at right angles to Figure 1.

In carrying the invention into effect, we 35 employ a can 10 which is equipped at one side thereof with a handle 11 while at its

upper end the can is provided with an outlet 40 nipple 12 which may be integral with the can, or, if preferred may be soldered or otherwise connected thereto. The nipple is provided with a bottom wall 13 and fixed

45 at its upper end to said wall is a discharge tube 14 extending for a portion of its length downwardly into the can axially thereof, while, as shown in Figure 1, the lower end portion of the tube is bent to extend toward one side of the can and terminates near the bottom thereof. Detachably connected with the nipple 12 is a tapered outlet spout 15

provided at its larger end with a base flange 16 resting upon the outer end edge of the 50 nipple 12, and screwed over the nipple is a collar 17 coacting with said flange for clamping the spout in position.

55 Fixed to the wall of the can above the handle 11 is, as shown in Figure 1, a packing gland 18 which projects obliquely into the can and slidable through said gland is a

valve rod 19. A suitable packing 20 is arranged in the gland and screwed into the outer end of said gland is a nut 21 adjustable for compressing the packing about the valve 60 rod. Fixed to the discharge tube 14 near the lower end thereof is a guide 22 slidably supporting the lower end portion of the valve rod and formed on said rod at its lower end is a laterally directed terminal 23 upon which 65 is mounted a tapered valve 24 fitting in the lower end of said tube. Fixed to the rod 19 in spaced relation to the guide 22 is a collar 25 and surrounding the rod to bear at one end against the guide and at its opposite 70 end against the collar, is a spring 26 normally holding the valve closed. Removably screwed upon the valve rod at its outer end is a knob 27.

Upstanding from the upper end of the can 75 10 at one side of the nipple 12 is, as shown in Figure 2, a filler tube 28 and slidably fitting through said tube is a pump cylinder 29 provided at its upper end with an out-turned annular flange 30. Resting upon the 80 upper end edge of the tube and underneath the flange 30 is a gasket 31 and screwed upon the tube 28 is a cap 32 compressing the gasket and binding the pump cylinder in position. Depending axially from the lower 85 end of the pump cylinder is a nipple 33 in which is formed a valve seat 34 at the lower end of an air passage 35 through the bottom wall of said cylinder, and freely mounted in the nipple to cooperate with the seat 34 is 90 a ball valve 36. Screwed upon the lower end of the nipple is a cap 37 having an air passage 38 and confined by said cap is a spring 39 normally holding the valve 36 closed. Slidable through the cap 32 at the 95 upper end of the pump cylinder 29 is a pump rod 40 equipped at its lower end with an appropriate piston 41 and removably screwed upon the upper end of the rod is a knob 42.

To fill the can 10, the cap 32 is removed 100 and the pump cylinder 29 then withdrawn through the filler tube 28. Accordingly, oil may be readily poured into the can through said tube. The pump cylinder is then, of course, again arranged in position and the cap 32 applied. As shown in Figure 2, the cap 32 is provided with an air passage so that, as will now be understood in view of the foregoing, the pump rod 40 may be operated for forcing air into the can. The valve 36 will, of course, prevent the backflow of 105 any oil into the pump cylinder, so that the 110

air will be compressed within the can above the body of oil therein. Accordingly, when the valve 24 is subsequently opened by pressure of the thumb or finger on the knob 27 of the valve rod 19, the oil will be ejected through the discharge tube 14 and forcibly delivered through the spout 15 of the can. Attention is now directed to the fact that since the pump cylinder 29 is removable, access may be readily had at any time to the valve 36 and associated parts while by unscrewing the cap 32, the pump rod 40 may be removed to permit access to the piston 41. The pump may thus be easily repaired and maintained in efficient working condition. Furthermore, it is to be noted that by pressing downwardly on the knob 27 of the valve rod 19 until the valve 24 clears the lower end of the tube 14, the rod may then be rotated for swinging the valve to one side of the tube. Accordingly, by then removing the spout 15, a wire or the like may be introduced through the tube 14 for cleaning the tube. Clogging of the tube may thus be readily overcome.

Having thus described the invention, what we claim is:

1. A hand oiler including a can having a discharge tube extending downwardly therein with its inner lower end portion extending diagonally, a handle carried by said can, a guide carried by the diagonally disposed inner end portion of said discharge tube, a valve rod extending into said can and disposed parallel to the inner end portion of said discharge tube with its lower end portion slidably engaged with said guide and its upper end portion extending externally of the can adjacent said handle, said valve rod be-

ing provided at its lower end with a laterally directed terminal, a valve carried by said terminal for closing the lower end of said tube, a spring yieldably holding said rod against inward movement with said valve normally closing the lower end of said tube, said rod being movable downwardly into the can against the action of said spring by pressure applied to its outer end until the valve clears the lower end of said tube and being rotatable to dispose the valve at one side of the tube, and an air pump carried by said can for compressing air therein.

2. A hand oiler including a can having a discharge tube extending downwardly therein with its inner lower end portion extending diagonally, a handle carried by said can, a guide carried by the diagonally disposed inner end portion of said discharge tube, a valve rod extending into said can and disposed parallel to the inner end portion of said discharge tube with its lower end portion slidably engaged with said guide and its upper end portion extending externally of the can above the handle and adjacent thereto, a closure for the lower end of said tube connected with the lower end of said rod, a spring yieldably holding said rod against inward movement with said valve normally in a closing position, said rod being moved inwardly to unseat said valve by pressure applied to the outer end of the rod, and means for the delivery of compressed air into said can.

In testimony whereof we affix our signatures.

FRED L. TICE. [L. S.]
CARL TICE. [L. S.]
